BOLT MAKING MACHINE

William L. Clouse, Tiffin, Ohio, assignor to The National Machinery Company, Tiffin, Ohio, a corporation of Ohio

Application May 9, 1933, Serial No. 670,109

21 Claims. (Cl. 10—12)

This invention relates to bolt making machines and the like of the type in which a blank is subjected to a plurality of successive operations at different stations or dies, as in the machine disclosed by the co-pending application of Earl R. Frost, Serial No. 639,054, filed October 22, 1932, and is particularly concerned with a blank transfer mechanism for carrying the blanks from one station to another.

10 In machines of this general type, it is desirable to perform an operation upon a blank at each die station during each cycle of the machine, and to transfer each blank to the next successive station during the inoperative portion of the cycle, so as to produce a completed blank during each cycle 15 of the machine. The purpose of this arrangement is primarily to maintain the rate of production of completed blanks as high as possible with a minimum of intermediate handling. It is found, however, that in many instances the limiting factor on the speed of production of multi-station machines of this type is the speed at which the blank transfer mechanism can be operated.

The present invention embodies the inventions 25 claimed broadly in my co-pending application, Serial No. 670,107, filed May 9, 1933 and has for its principal object an arrangement of the parts so that each set of transfer fingers moves through a path forming a closed curve from one die station to another so that the fingers may grasp a blank at one station and release the same at the other. A further object of the present invention is to provide a simplified movement and operating mechanism for blank transfer fingers so that 30 the fingers move, in carrying a blank through a different path than that through which the fingers move when returning empty to receive another blank so that it is only necessary to arrange half of the cycle of movement of the blank transfer fingers in a path out of line with the header slide. An additional object of it is the provision of stop members for transfer mechanisms to positively stop the motion of the fingers and align them with the dies, one of said members being movable and the other fixed relative to the dies. Another object is to provide a smooth, positive and relatively rapid movement for the blank transfer mechanism permitting accurate alignment of the sets of fingers with the die stations, 45 a simple and rugged driving mechanism, and relatively rapid action with a minimum of strain on the parts.

Another object of this invention is to provide a blank transfer mechanism which may be easily moved as a unit clear of the dies whenever it is

desired to gain access to the latter and subsequently returned to positive position without disassociating the parts or affecting the timing of the mechanism with respect to the header slide.

The foregoing and other objects and advantages will become apparent in view of the following description taken in conjunction with the drawing, wherein:

Figure 1 is a fragmentary plan view of the forward extremity of a bolt making machine showing the improved transfer mechanism of the present invention applied thereto;

Figure 2 is a sectional elevation taken substantially on the line 2—2 of Figure 1; and

Figure 3 is a detail view of a locking and indexing device.

Referring to the drawing in detail, I have illustrated the invention in connection with a machine of the type shown in my aforesaid co-pending application. The numeral 5 designates a bed frame 20 having at its forward extremity a die breast 6. A header slide 7 is mounted to reciprocate longitudinally in the frame 5 and is provided with a plurality of punches 8, 9 and 10 adapted to cooperate with dies 11, 12 and 13 in the breast 25 plate 6. Considering the machine to be designed to carry out the process described in the above application, then the die 11 would be an extrusion die into which the bolt blank is pressed by the punch 8 to reduce the diameter of the major portion of the blank; the die 12 also an extrusion die for extruding the thread-receiving portion of the bolt shank, the co-operating punch 9 being a heading tool which presses the blank into the die and also upsets the previously unextruded portion 30 35 to form a head; while the die 13 would be a holding die which co-operates with the hollow trimming punch 10 which trims the upset heads of the blanks to the desired polygonal form.

Wire or rod stock S is fed through suitable 40 guides in the frame of the machine and engages an adjustable stock gauge 14. A cut-off arm 15 of any desired type is arranged to engage the stock, shear off blanks of the desired length and carry the same into alignment with the die 11. 45 The arm may be rocked or reciprocated by any suitable means, not shown, and at its upper end moves in a guide 16.

During each cycle of the machine, arm 15 is oscillated to shear off a blank and carry the same 50 into alignment with the die 11 during the time the header slide 7 is retracting and then returns to its initial or cut-off position to receive another blank while the slide is moving forward into engagement with the work.

It will be understood, of course, that any desired combination and types of punches and dies may be used as well as any desired type of cut-off means, the present improved transfer mechanism not being limited by the illustrated embodiment.

The transfer mechanism is arranged to carry blanks from the die 11 to the die 12, and from the die 12 to the die 13 in synchronism with the movement of the header slide.

The numerals 17, 17a and 18, 18a designate co-acting sets of transfer fingers which are provided at their blank engaging ends with hardened wear plates 19, 19a, which are formed with recesses to receive a blank, and beveled end surfaces to permit the fingers to be forced open and snap over a bolt blank. Each pair or set of fingers is provided with a compression spring 20 mounted on a bolt or screw 21, by means of which the fingers are maintained under proper tension. An abutment screw 22 is mounted in each finger 17, 18 to accurately position the fingers laterally relative to each other, while each finger 17a, 18a is mounted on an eccentric stud 23 which may be adjusted angularly to accurately position the blank-gripping ends of the fingers relatively to the dies.

The co-acting pairs of fingers 17, 17a, and 18, 18a are pivotally anchored at their upper ends to a support or bracket 24 which is provided with bearing bosses 25 and 25a at opposite ends thereof. The bearing 25 is mounted on a crank arm, which in the embodiment illustrated takes the form of an eccentric connection by means of a pin 26 to a spider gear 27. The bearing 25a is similarly mounted on a crank arm with respect to the driving shaft 32, the two crank arms having the same throw and angular relation. As shown the bearing 25a is eccentrically connected by means of a pin 28 to a gear 29. Means are provided to maintain the eccentric mountings of the bearings 25 and 25a in the proper relation, consisting of an idler gear 30 engaged between the gears 27 and 29.

The gears 27 and 30 are journaled on a hinged plate or bracket 31 which has formed at one side thereof an upright portion 31a to accommodate this mounting, while the gear 29 is fixed or splined on one end of a drive shaft 32 which is mounted in bearing brackets 33 formed on the bed frame 5. The drive connection between the hub of the gear 29 and pin 28 is preferably reinforced by a link or web 34. The plate or bracket 31 is provided with hinge bearings 35 which are mounted on the shaft 32, and said plate is adapted to lie flush against the bed frame 5 and, as shown, is secured in such position by a bolt 36. It will be seen that by loosening this bolt, the plate 31 may be swung upwardly, carrying the transfer finger assembly and gears 27 and 30 therewith, the latter turning about the gear 29 and functioning as a planetary system during this movement.

Shaft 32 is intermittently driven in one direction by any convenient drive mechanism, which as illustrated is a Geneva gear.

A gear 37 is fixed to the end of shaft 32 and meshes with a gear 38 which is journaled to the frame and which in turn is driven by a Geneva gear 39. The latter is fixed on a shaft 40 journaled to the bed frame of the machine and driven from the main crank shaft of the machine in a fixed relation to the movement of the header slide. The intermittent drive may conveniently be obtained by straps 38a fixed in pairs

to the rear face of the gear 38 and arranged to receive pins 39a mounted on the Geneva gear 39. In the arrangement shown there are six pairs of guides 38a and two diametrically opposed pins 39a so that each 180 degrees of the movement of the shaft 40 turns the gear 38 through 60 degrees. Obviously any desired gear ratio may be selected, the sizes of the gears being co-ordinated with the Geneva drive so that the drive shaft 32 of the transfer mechanism turns through two half revolutions separated by two rest periods during each cycle of the movement of the header slide.

A locking and indexing mechanism may be associated with the Geneva drive to lock the parts against movement during the rest periods and accurately align the transfer fingers with the dies. As shown this arrangement consists of a series of tapered sockets 41 carried on the front face of the gear 38 and arranged to receive a tapered locking pin 42 slidably mounted in a bracket 43 on the bed frame. A spring 44 normally holds the pin 42 pressed toward the sockets 41 and an arm 45 driven by a cam 46 secured to the shaft 40 is arranged to retract the pin 42 out of engagement with the sockets and hold it retracted during the time the gear 38 is being moved by one of the pins 39a. As the gear 38 comes to rest at the conclusion of one of the cycles of movement as illustrated in Figure 2, the cam 46 releases the arm 45 and allows the pin 42 to drop into one of the sockets and accurately center and lock the disc 38 until the other pin 39a comes into engagement with a pair of guide strips 38a.

The header slide 1 which is driven by a crank from the main crank shaft of the machine moves forward into position to perform the desired operations upon the blanks held in the dies 11, 12 and 13. As it recedes the cut-off arm 15 cuts off a length of stock and carries it over into alignment with the first die 11. At the next stroke of the header slide the stock held in the die 11 is upset or acted upon in the desired manner. As the header slide begins to recede an ejector pin 45 ejects the stock from the die 11. When the blank is partially ejected the fingers 17 and 17a move downwardly in an arcuate path toward the blank and snap over the blank while it is supported in the die. The transfer fingers then rest until the completion of the stroke of the ejector and until the header slide has receded far enough to completely release the blank. The transfer mechanism then starts the second part of its movement and the fingers 17 and 17a move downwardly and to the right in a substantially semi-circular path and then upwardly into alignment with the opening in the die 12. At this point the movement of the transfer mechanism again ceases leaving the blank carried by the fingers 17 and 17a aligned with the die 12.

As the header slide moves forward it engages the blank held in the fingers and starts to press it into the die 12. After the blank has moved into the die 12 a sufficient distance to be firmly held, the transfer mechanism again moves causing the fingers 17 and 17a to rise up and move to the left, snapping off the blank and clearing the punch carried by the header slide. While the header is acting upon the blank the fingers move to the left through their arcuate path above the punches carried by the header slide and again move downwardly and snap on to the next blank being ejected from the die 11 when the header slide has moved back sufficiently. The fingers 18 and 18a transfer blanks from the die 12

to the die 13 in exactly the same manner and at the same time, both sets of fingers being carried by the plate 24.

This movement of the transfer fingers is effected through the eccentric or crank mounting of the bars 25 and 25a formed on the ends of the plate 24. The plate is retained at all times substantially parallel to the line of the dies 11, 12 and 13, but the two ends thereof are rotated about the shaft 32 and the center upon which the gear 27 is journaled. The two gears 27 and 28 are caused to move together by the intermediate idler gear 30 and the intermittent motion is transmitted to the gear 29 through the shaft 32 by the Geneva gear 38 and 39. During one complete cycle of the motion of the transfer mechanism each pair of fingers describes a complete circle with two rest points in line with the two dies between which the fingers operate. The duration of the rest periods when the fingers are aligned with the dies is preferably made as short as possible in order to increase the time available for the movement of the fingers between the dies. The time during which the fingers are stationary when the blanks are being delivered to the dies 12 and 13 need be only sufficient to permit the blanks to be pressed into the dies far enough to securely retain them so that the fingers can snap off the blanks and when the fingers are receiving the blanks at the opposite end of their stroke they need engage the blanks only sufficiently in advance of complete ejection to insure the blanks being held in position while the fingers are pressed apart and snap over them.

When it is desired to change, adjust or replace the dies 11, 12 or 13 they may be readily exposed and reached by releasing the bolt 36 and swinging the bracket 31 upwardly and to the left as seen in Figure 2 about the shaft 32 as an axis. The gear 38 being held stationary either by one of the pins 39a or the locking plunger 42, the gear 29 is likewise held stationary and the gear 30 and the gears 27 rotate about the gear 29. When the bracket is again returned to its normal position the gears 30 and 27 return to their initial positions so that the timing of the machine is not affected.

Although the preferred embodiment and operating mechanism is disclosed, it will be understood that the two crank arms upon which the opposite ends of the supporting plate are mounted may be maintained in synchronism by linkage instead of gears if desired and similarly that cams or any other suitable arrangement may be used to provide the intermittent drive in place of the Geneva gear. Numerous other modifications and re-arrangements of parts may be resorted to without departing from the scope of the invention as defined in the following claims.

I claim:

1. In a bolt making machine, in combination, a pair of dies to receive blanks, a header slide co-acting with said dies and carrying hammers to act upon the blanks held therein, means for cutting off lengths of continuous stock and carrying the same into alignment with the first of said dies and transfer mechanism for carrying blanks from the first die to the second including gripping fingers and means to move the same from one die to the other and back to the first die through a path forming a closed curve.

2. In a heading machine, in combination, a pair of dies, a pair of reciprocating hammers co-operating with said dies to work upon blanks held therein, means for cutting off lengths of continuous stock and carrying the same into alignment with

the first of said dies, and transfer mechanism for transferring lengths of stock from the first die to the second comprising gripping means driven in timed relation to the header slide and moving from the first die to the second through a curved path disposed on one side of a line connecting said dies and moving from the second die to the first on a curved path disposed on the other side of said line.

3. In an upsetting and heading machine, a plurality of dies arranged in a straight line, a reciprocating header slide carrying a plurality of hammers co-operating with said dies, means for cutting off lengths of continuous stock and carrying the same into alignment with the first of said dies and gripping means arranged to engage a blank ejected from the first die, carry the same through an arcuate path disposed on one side of the line of said dies into alignment with the second die while the header slide is retracted, and move through a closed path disposed on the other side of said line of dies from the second die to the first die while the header slide is in engagement with the work.

4. In combination, a plurality of dies arranged in a straight line and transfer mechanism for transferring blanks from one die to another comprising a pair of gripping fingers and means for moving said fingers through a closed circular path so that the ends of the fingers approach and snap over a blank ejected from one die and recede from and snap off of a blank carried thereby when the same has been engaged by the other die.

5. In an upsetting and heading machine, in combination, a plurality of dies arranged in a straight line, a header slide carrying hammers co-operating with said dies and transfer mechanism comprising a supporting member disposed on one side of the line of dies and having gripping fingers projecting toward the dies, and means for simultaneously moving each end of said supporting member through a circular path to alternately align each set of fingers with one of two adjacent dies.

6. In an upsetting machine, in combination, a plurality of dies arranged in a straight line, and transfer mechanism for transferring blanks from one die to another including a supporting member disposed on one side of the line of said dies, a pair of co-operating gripping fingers carried by said supporting member and projecting toward said dies, and means for moving said supporting member in a complete circular path to alternately align said fingers with two of said dies.

7. In an upsetting machine, a plurality of dies arranged in a straight line, a supporting member disposed on one side of the line of said dies, a pair of crank arms journaled to said supporting member at spaced points, gripping means carried by said supporting member and projecting toward said dies, and means for simultaneously rotating said crank arms in the same direction to move each of said spaced points on said supporting member through a complete circular path.

8. In an upsetting and heading machine, a plurality of dies arranged in a straight line and transfer mechanism for moving a blank from one die to another comprising a supporting member having blank gripping means extending therefrom toward said dies, a pair of crank arms connected to said supporting member at spaced points, and means for driving said transfer mechanism arranged to rotate each of said crank arms through a half revolution in the same direction to bring said blank gripping means into alignment with

- one of said dies, and stop the motion at such point and subsequently rotate said crank arms through another half revolution in the same direction to bring said gripping means into alignment with 5 another of said dies.
9. In an upsetting machine, in combination, a plurality of dies arranged in a straight line, a header slide carrying hammers co-operating with said dies, means for cutting off lengths of continuous stock and carrying the same into alignment with the first of said dies, and transfer mechanism arranged to carry lengths of stock from the first die to the second and from the second to the third including a supporting member disposed at one side of the line of said dies and having gripping fingers projecting toward said dies, a pair of rotating members having eccentric connections with said supporting member at spaced points and means driven in timed relation to said header slide to move said rotating members through a half revolution in the same direction and subsequently through another half revolution in the same direction with a rest period between the two movements to move the spaced 10 points on said supporting member through complete circular paths.
10. In a bolt making machine, a bed frame, a plurality of aligned dies supported by said frame, a reciprocating header slide having a punch co-operating with each die, means for shearing stock into suitable lengths to form blanks and for carrying the blanks to the first of said dies, co-acting sets of transfer fingers adapted to engage and releasably retain said blanks, a support for said fingers, and means for intermittently moving said support and fingers in a complete circular path in synchronism with the reciprocation of the header slide to effect transfer of bolt blanks from one die to another.
11. In a bolt making machine, a bed frame, a plurality of aligned dies supported by said frame, a reciprocating header slide having a punch co-operating with each die, means for shearing stock into suitable lengths to form blanks and for carrying the blanks to the first of said dies, co-acting sets of transfer fingers adapted to engage and releasably retain said blanks, a support for said fingers, and means for moving said support and fingers in a 360 degree arc in synchronism 40 with the reciprocation of the header slide and for interrupting the movement at approximately each 180 degrees of the arc at points which bring the transfer fingers in blank gripping registration with the dies to effect transfer of bolt blanks from one die to another.
12. In a bolt making machine, a bed frame, a plurality of aligned dies supported by said frame, means for shearing stock into suitable lengths to form blanks and for carrying the blanks to the first of said dies, co-acting sets of transfer fingers adapted to engage and releasably retain said blanks, a supporting frame on which said fingers are mounted, interconnected gears having an eccentric pivotal connection with said frame, and means for intermittently driving said gears to move said fingers in an arcuate path into blank gripping registration with said dies and thereby effect transfer of bolt blanks from one die to another.
13. In a bolt making machine, a bed frame, a plurality of aligned dies supported by said frame, means for shearing stock into suitable lengths to form blanks and for carrying the blanks to the first of said dies, co-acting sets of transfer fingers adapted to engage and releasably retain 70 said blanks, a supporting frame on which said fingers are mounted, interconnected gears having an eccentric pivotal connection with said frame, and a drive member for said gears, said member being adapted to impart an intermittent approximately 180 degrees' rotation to said frame and fingers to effect transfer of bolt blanks from one die to another.
14. In a bolt making machine, a bed frame, a plurality of aligned dies supported by said frame, means for shearing stock into suitable lengths to form blanks and for carrying the blanks to the first of said dies, co-acting sets of transfer fingers adapted to engage and releasably retain said blanks, a supporting frame on which said fingers are mounted, and means for imparting a rotary transfer movement to said frame and fingers comprising a pair of gears to which said frame is eccentrically pivotally connected and an intermediate idler gear, a shaft on which one 10 of said first-named gears is fixed, and an intermittent drive means for said shaft.
15. In a bolt making machine, a bed frame, a plurality of aligned dies supported by said frame, means for shearing stock into suitable lengths to form blanks, a blank transfer assembly comprising co-acting sets of transfer fingers adapted to engage and releasably retain said blanks and means for bodily actuating said fingers to effect transfer movements thereto, a drive shaft for 15 said actuating means, and a support for said assembly having a hinge-like pivotal connection with said shaft and removably clamped to said frame whereby when it is desired to gain access to said dies the support may be released from the 20 frame and together with said assembly swung back clear of the dies.
16. In a bolt making machine, a bed frame, a plurality of aligned dies supported by said frame, means for shearing stock into suitable lengths to 25 form blanks and for carrying the blanks to the first of said dies; a blank-transfer assembly comprising co-acting sets of transfer fingers, a supporting frame for said fingers, a pair of gears to which said support is eccentrically and pivotally connected and an intermediate idler gear, 30 a drive shaft for said gears and to which one of said gears is secured, and a bracket plate for supporting said assembly, said plate being pivotally connected to said shaft and clamped to said 35 frame.
17. In a machine of the class described, a bed frame having a die breast with a plurality of dies mounted thereon, means for transferring blanks from one die to another including a unit 40 consisting of a carriage having a plurality of sets of transfer fingers pivotally connected thereto and mechanism for imparting transfer movements to said fingers, means for driving said mechanism, and a supporting bracket for said unit pivotally connected to said frame whereby 45 when it is desired to gain access to said dies the unit as a whole may be swung back to clear the dies and adjacent parts, said driving means being arranged so that the unit may be swung back without disconnecting the actuating mechanism therefrom.
18. In a machine of the class specified, a bed frame having a die breast with a plurality of dies mounted thereon, means for transferring 50 blanks from one die to another including a unit consisting of a carriage having mounted thereon a plurality of sets of transfer fingers and mechanism for imparting transfer movements to said fingers, means for driving said mechanism 55

- nism including a driving member located adjacent thereto and having a driving connection therewith, and a supporting member for said unit pivotally connected to said frame whereby when it is desired to gain access to said dies the unit as a whole may be swung back to clear the dies and adjacent parts, said drive member being connected to said mechanism in a manner such that the unit may be swung back without breaking said driving connection.
- 10 19. In a machine of the class described, a bed frame having a die breast with a plurality of transversely aligned dies mounted thereon, means for transferring blanks from one die to another including a unit consisting of a carriage having a plurality of sets of transfer fingers pivotally mounted thereon and mechanism for imparting transfer movements to said fingers, said mechanism including a drive gear, means for driving said mechanism including a main drive gear mounted adjacent to and constantly in mesh with said first-named gear, and a supporting bracket for said unit pivotally connected to said frame whereby when it is desired to gain access to said dies the unit as a whole may be swung back to clear the dies and adjacent parts, said gears being arranged so that the unit may be swung back and forth in an arc without disconnecting the gears from one another.
- 25 20. In combination, a plurality of dies, recipro-
- cating means for acting upon blanks held in said dies, and transfer mechanism for carrying blanks to each of said dies in sequence comprising a support carrying sets of blank gripping fingers, said support being journaled at spaced points upon eccentrically rotatable members, means for turning said members to move each of said sets of blank gripping fingers from a position in alignment with one die to a position in alignment with the next adjacent die and inter-engaging wedging members for positively stopping the movement of said blank gripping fingers and aligning the same with said dies.
- 20 21. In combination, a plurality of dies, reciprocating means for acting upon blanks held in said dies, and transfer mechanism for carrying blanks to each of said dies in sequence comprising a support carrying sets of blank gripping fingers, said support being journaled at spaced points upon eccentrically rotatable members, means for turning said members to move each of said sets of blank gripping fingers from a position in alignment with one die to a position in alignment with the next adjacent die, a means to stop and align said blank gripping fingers comprising a cone shaped member and a cone receiving member, one of said members fixed with respect to said dies and the other of said members movable with said blank gripping fingers.
- 25
